UNITED STATES PATENT OFFICE.

WILBER THOMAS, OF QUINCY, ILLINOIS.

PICKET FENCE.

SPECIFICATION forming part of Letters Patent No. 284,685, dated September 11, 1883.

Application filed January 27, 1883. (No model.)

To all whom it may concern:

Be it known that I, WILBER THOMAS, a citizen of the United States, residing at Quincy, in the county of Adams and State of Illinois, 5 have invented a new and useful Picket Fence, of which the following is a specification, reference being had to the accompanying drawings.

This invention relates to that class of picket fences in which the pickets are held by encircling-strands of wire.

The invention has for its object to provide a simple, inexpensive, durable, ornamental, and efficient fence, in which neither the pickets nor wire are liable to displacement.

In the drawings, Figure 1 is a perspective view of a portion of my improved fence. Fig. 2 is a transverse vertical sectional view thereof. Fig. 3 is a detail view in elevation, showing a picket in position. Fig. 4 is a detail cross-section.

Referring to the drawings, A designates a longitudinal base-strip, which is preferably formed of a single piece or strip, and may be 25 formed with an ornamental or molded face, B, as shown. This base-strip preferably rests on a longitudinal base-board, C, but can, if desired, rest directly on the ground. The strip A is provided with a longitudinal top shoulder, D, in rear of which is a longitudinal vertical flange or raised portion, E, the office of 30 which will be presently described.

F designates the pickets of the fence, each of which is formed tapering its entire length. 35 The pickets are retained by encircling coils or twists G in the longitudinal strands H of twisted securing-wire, and are placed with their larger end I resting on the shoulder D of the base-strip A and against the flange E.

In smooth shapes of pickets having a uniform width and thickness, the wires are liable to displacement from accidental or intentional blows, that in almost every instance are delivered from above. Pickets of this kind are also free to be easily and readily withdrawn 40 from the wires; but in my improved fence these disadvantages are entirely obviated. The base rail or strip prevents displacement of the picket downwardly, and the flange on the said base strip obviates displacement of the pickets by being forced inwardly. The securing-wires cannot be displaced downwardly, because the diameter of the picket increases in 45 that direction.

No nails are required in the construction of 55 my improved fence, as the base-piece is formed of a single strip or rail, and it is not necessary to nail the pickets. Rotting and decay of the pickets and base are thus obviated, and water can flow off the shoulder of the base-rail.

I claim as my invention—

As an improvement in picket fences, the combination of a longitudinal base-piece having a longitudinal top shoulder and corresponding raised flange in rear thereof, longitudinally-tapered pickets, having their larger end resting on the said shoulder and prevented from backward displacement by the flange, and the securing-strands of wire encircling the pickets, as set forth.

In testimony that I claim the foregoing as my own I have hereto affixed my signature in presence of two witnesses.

WILBER THOMAS.
